UNITED STATES PATENT OFFICE.

JAMES H. SEIBERLING, OF JONESBORO, INDIANA.

CASING FOR PNEUMATIC TIRES.

932,815.

Specification of Letters Patent. Patented Aug. 31, 1909.

Application filed March 3, 1909. Serial No. 481,125.

To all whom it may concern:

Be it known that I, JAMES H. SEIBERLING, a citizen of the United States, and a resident of Jonesboro, in the county of Grant and 5 State of Indiana, have invented a new and Improved Casing for Pneumatic Tires, of which the following is a full, clear, and exact description.

The invention relates to wheels for bicycles, motor cycles and other vehicles having 10 a casing or a shoe containing an inner inflatable tube.

The object of the invention is to provide a new and improved casing or shoe for pneumatic tires, arranged to permit its convenient and ready application on either a single clench or double clench style of wooden rim, the casing being provided for this purpose with separable abutting edges 20 and single exterior locking ribs arranged at equal distances from the said edges, the portion of the casing extending from the base of each rib to the corresponding edge gradually diminishing in thickness and forming 25 a pliable non-clenching, closing flange.

A practical embodiment of the invention is represented in the accompanying drawings forming a part of this specification, in which similar characters of reference indicate corresponding parts in both views.

Figure 1 is a sectional perspective view of the improvement, showing the casing applied to a single clench wooden rim; and Fig. 2 is a like view of the same, illustrating 35 the casing applied to a double clench wooden rim.

Clencher casings or shoes, as heretofore constructed, were either of the single clench or the double clench style, to be used on correspondingly shaped single clench or double clench rims, respectively. My improved clencher casing or shoe, presently to be described in detail, can be used on either a single or a double clench rim.

45 The casing or shoe A, for containing the inner inflatable tube B, is adapted to be clenched to either a single clench rim C, as shown in Fig. 1, or to a double clench rim C', as illustrated in Fig. 2. For the purpose 50 mentioned the casing A is provided with abutting or meeting edges A', and single exterior locking ribs A² are formed on the casing at equal distances from the edges A'.

The portion A³ of the casing extending from the base of each rib A² to the corresponding edge A', gradually diminishes in thickness and forms a pliable non-clenching, closing flange. The casing A is also provided with an integral interior flap A⁴ adapted to overlap the joint formed by the edges A', one 60 end of the flap being integral with one side of the casing a distance from the edge thereof, and the flap A⁴ being of a width to extend well onto the opposite side of the casing A, as will be readily understood by reference to the drawings.

Now when the casing A is placed in position on the single clench rim C, as shown in Fig. 1, then the flanges A³ on being pressed outward by the inserted tube B cause firm 70 engagement of the ribs A² with the recesses C² of the rim C, to securely hold the casing A in position on the rim C. When the casing A is applied to the double clench rim C', shown in Fig. 2, then the ribs A² engage 75 the recesses C³, and the flanges A³ step over the rib C' to cause the edges A' to firmly meet in the center of the rim C', thus causing a firm contact of the ribs A² with the recesses C³ in the outer ridges of the rim C'. 80

From the foregoing it will be seen that by the arrangement described, the same casing A can be readily used on either single clench wooden rims or double clench wooden rims.

Having thus described my invention, I 85 claim as new and desire to secure by Letters Patent:

A casing for single clench or double clench rims, comprising a strip having edges adapted to abut, said strip being of greater width 90 than the circumference of the tube to be contained therein, so that the edges will abut with their inner faces, one of said edges having an integral tongue for overlapping the inner face of the other edge, each of 95 said edges having on its outer face an exterior locking rib, the ribs being arranged at equal distances from the edges for the purpose set forth.

In testimony whereof I have signed my 100 name to this specification in the presence of two subscribing witnesses.

JAMES H. SEIBERLING.
